UNITED STATES PATENT OFFICE.

FRANCES SOKOL, OF CHELSEA, IOWA.

BARRETTE.

Application filed August 5, 1925. Serial No. 48,290.

This invention relates to improvements in hair fasteners and more particularly to barrettes.

One of the important objects of the present invention is to provide a barrette which is of such construction as to enable the same to be readily and easily attached to the hair for the purpose of holding several strands of the hair without necessitating the disturbing or mussing up of the hair which frequently results with the use of hair barrettes now generally used.

A further object is to provide a hair barrette of the above mentioned character which includes a pair of complementary clamping members, the same being detachably fastened together, one of said clamping members being adapted to be disposed beneath the strands of hair to be fastened, while the other clamping member is disposed over said strands of hair.

A still further object is to provide a hair barrette of the above mentioned character which is simple in construction, inexpensive, strong, and durable and further well adapted to the purpose for which it is designed.

Other objects and advantages of the invention will become apparent during the course of the following description taken in connection with the accompanying drawing.

In the accompanying drawing forming a part of this application and in which like numerals designate like parts throughout the same:

Figure 1 is an elevational view of my improved hair barrette, showing the same in use.

Figure 2 is a top plan view thereof, and

Figure 3 is a disassembled view of the complementary clamping members.

In the drawing, wherein for the purpose of illustration is shown the preferred embodiment of my invention, the numeral 1 designates generally my improved hair barrette, the same comprising the complementary clamping members 2 and 3, respectively, each of which is formed of an elongated thin strip of any suitable metal provided the same is rendered flexible, the strips being of a suitable length.

The complementary clamping members are detachably secured together in spaced relation through the medium of any suitable fastening means, and in the present instance, I have employed snap fasteners for this purpose. The male or head sections of the snap fasteners are arranged on the inner side of the strip 2 adjacent the respective ends thereof as indicated at 4, and the female or socket sections 5 of the snap fasteners are carried by the inner side of the complementary strip 3 at the respective ends thereof. As is obvious from the construction shown in Figure 2, the snap fasteners provide a means for spacing the strips from each other so that the strands of hair may be received between the strips.

In use, the strip 3 is placed beneath the strands of hair to be fastened, and then the strip 2 is placed on top of these strands of hair so that the heads 4 will be received within the sockets 5 at the respective ends of the strips, and thereby enable the clamping members to be secured together as to hold the strands of hair between the strips comprising the barrette in the manner as clearly illustrated in the drawing.

The use of a hair barrette of the above mentioned character will save considerable time and labor, and furthermore will not cause the hair to be disarranged or otherwise mussed up as frequently results when hair barrettes of the character now on the market are used.

If desired, the barrette may be provided with any suitable ornamentation to render the same attractive when worn on the hair.

While I have shown the preferred embodiment of my invention, it is to be understood that minor changes in the size, shape, and arrangement of parts may be resorted to without departing from the spirit of the invention, and the scope of the appended claim.

Having thus described the invention, what I claim as new and desire to secure by Letters Patent is:—

A hair barrette of the class described comprising a pair of separate complementary elongated flat metallic strips of equal

length, said strips being of the same width throughout their entire length, between which strips strands of hair are to be fastened, a pair of socket members arranged on the inner face of one strip adjacent the respective ends thereof, and heads carried by the inner face of the complementary strip

and adapted to be received in the respective socket members whereby the strips are detachably secured together.

In testimony whereof I affix my signature.

FRANCES SOKOL.
